DI-SALICYLATE OF 7-CHLORO - 4 - (4' - DI-ETHYLAMINO-1' - METHYLBUTYLAMINO) QUINOLINE

Charles F. Geschickter, Rock Creek Hills, and Martin I. Rubin, Silver Spring, Md., assignors to Geschickter Fund for Medical Research, Inc., New York, N. Y., a corporation of New York

No Drawing. Application September 30, 1949,
Serial No. 118,998

1 Claim. (Cl. 260—286)

1

The present invention relates to a new therapeutic agent. More particularly the present invention relates to a new antihistamine especially effective on allergic diseases affecting the respiratory tract.

The antihistamines in current use have not proven to be entirely effective in the control of many cases of asthma and non-seasonal rhinitis. Where effective, they afford symptomatic rather than permanent relief or cure. The same is true of the desensitizing injections of protein substances which have the added disadvantage of requiring elaborate intradermal testing to determine the nature of the sensitizing agent or allergen.

In accordance with the present invention certain new antihistamine substances have been found which concentrate especially in the respiratory epithelium and which had a prolonged duration so that a serum level could be established and maintained.

The particular antihistamines which are the subject of the present invention are amino-quinolines and in particular the di-salicylates of 7-chloro 4 substituted quinolines. The particular salicylates involved are the di-salicylates of compounds represented by the following formula:

wherein R represents a polymethylene chain of from 2 to 6 carbon atoms preferably substituted by a hydroxy radical or a methyl radical and R₁ and R₂ are alkyl radicals of from 2 to 6 carbon atoms.

Especially desirable compounds were the di-salicylates of 7-chloro-4 - (4' - diethylamino-1' - methylbutylamino) quinoline and 7-chloro-4 - (3' - diethylamino-2' - hydroxypropylamino) quinoline.

The above compounds were administered to a number of patients and they were found to have a low toxicity and that plasma concentrations as high as 0.3 mg. per liter could be maintained on a daily dose of 0.4 gr. The compounds showed a high retention in the tissue and body fluids with a high concentration in the respiratory tissue. They were found to have good results in various types of allergy.

2

The di-salicylate salts were prepared by reacting the known compounds 7-chloro-4-(4'-diethylamino-1'-methylbutylamino) quinoline and 7-chloro-4-(3'-diethylamino-2' - hydroxypropylamino) quinoline for a short period of time with a solution of salicylic acid in absolute ethyl ether. Preferably an amount of salicylic acid was used equivalent to in excess of 2 mols of salicylic acid to one mol of the aforesaid compounds. Thereafter the solution was decanted and the precipitate ground and extracted with successive portions of hot petroleum ether (70-90° C.). The residual solids showed on analysis the correct values for the di-salicylate salts. Apparently the compounds formed were in part quaternary salt combinations with the aforesaid amino quinolines. The compounds thus produced were suitably formed into proper dosage capsules.

The following specific examples serve to illustrate the present invention but are not intended to limit the same.

Example I

3 grs. of 7-chloro-4-(4'-diethylamino-1'-methylbutylamino) quinoline were added to a solution of 7.5 grs. of salicylic acid in 50 cc. of absolute ethyl ether. After thorough mixing the resultant precipitate was separated by decantation of the supernatant solution. The residue was ground and then extracted with three 50 cc. portions of hot (70-90° C.) petroleum ether. The residual solid, after removal of the petroleum ether, showed on analysis the correct values for the di-salicylate salt of 7-chloro-4-(4'-diethylamino-1'-methylbutylamino) quinoline.

Example II

3 grs. of 7-chloro-4-(3'-diethylamino-2' - hydroxypropylamino) quinoline were added to a solution of 7.5 grs. of salicylic acid in 50 cc. of absolute ethyl ether. After thorough mixing the resultant precipitate was separated by decantation of the supernatant solution. The residue was ground and then extracted with three 50 cc. portions of hot (70-90° C.) petroleum ether. The residual solid, after removal of the petroleum ether, showed on analysis the correct values for the di-salicylate salt of 7-chloro-4-(3'-diethylamino-2' - hydroxypropylamino) quinoline.

It will be obvious to those skilled in the art that various changes may be made without departing from the spirit of the invention and therefore the invention is not limited to what is described in the specification but only as indicated in the appended claim.

What is claimed is:

A new compound consisting of the di-salicylate of 7-chloro-4-(4'-diethylamino-1'-methylbutylamino) quinoline.
